METHOD OF FORMING AND APPLYING
SCREW CAPS TO CONTAINERSLeslie R. N. Carvalho, Toledo, Ohio, assignor to
The Closure Service Company, Toledo, Ohio, a
corporation of Ohio

Application October 25, 1934, Serial No. 749,899

3 Claims. (Cl. 226—86)

My invention relates to screw caps for bottles, jars and other containers, and contemplates a final forming of the cap after it has been initially applied to the screw threaded finish of the container.

The usual method of applying a screw cap to a screw threaded bottle finish develops certain difficulties. Frequently the caps will "cock up" on one side and fail to maintain the liner in perfect sealing engagement. Again, the lacquer on the inside of the cap, or the intervening liner, is sometimes mutilated by some slight roughness or irregularity during the turning movement of applying the cap on the finish of the bottle, thus producing "leakers". Another defect of the ordinary screw closure is that the uniformly rolled threads of the cap cannot take up the variations which develop in the molded threads of different containers even though produced on the same bottle machine.

To meet these objections, it has been proposed to draw the cap without threads, apply it to the finish of the bottle by top pressure, and while in this position, apply a rolling die which rolls the threads into the flange of the cap in conformity with the threads of the container finish. A cap of this type is superior to the ordinary screw cap, for the reason that uniform downward pressure is exerted on the liner to bring it into sealing engagement with the top of the finish and avoid the creeping action that is likely to be imparted to the liner in screwing the cap down on the jar and that oftentimes wrinkles the liner between the inside of the cap and the top of the bottle finish so as to prevent an even seal.

My present invention contemplates the similar procedure of applying the flanged cap to the container by direct down pressure, but at the same time utilizing this pressure, instead of a rolling die, to collapse the flange or skirt of the cap into the threads of the container to conform thereto, thus effecting a perfect gripping action of the cap upon and in sealing contact with the finish of the container, from which, however, it may be readily removed by an unscrewing movement like the ordinary screw cap, whenever it is desired to break the seal and expose the contents of the container.

An object of my invention is to provide a cap which will render a more perfect sealing engagement between the liner and the top of the finish, and in which the screw threads are given final form by collapsing the depending flange of the cap inwardly against the threaded exterior of

the finish, with the result that each cap is made to fit accurately the individual finish to which it is applied, regardless of variations in the latter.

Further objects appear from the ensuing description of the construction illustrated in the accompanying drawing in which:

Fig. 1 is a side elevation of my cap before applying it to a container.

Fig. 2 is a fragmentary sectional elevation of 10 the container, cap, sleeve and plate in assembled relation immediately prior to the application of top pressure.

Fig. 3 is a fragmentary sectional elevation of 15 the container and cap in sealed relation after top pressure has been applied and the plunger lifted.

Fig. 4 is a side elevation of the cap in its completed form and removed from the container.

Referring to Fig. 1 of the drawing, 10 is the 20 cap generally, including a circular top portion 11 and a depending flange or skirt 12. Within the cap is a liner 13 (Figs. 2 and 3). The upper part of the flange 12 has a slightly outturned bead 14 which may be plain or corrugated, as desired. 25 Below the bead is a light continuous thread 15. The skirt terminates in a curled or wire edge 16.

Referring, now, to Fig. 2, the cap is loosely fitted to the finish 17 of a container, the screw thread 15 of the cap engaging loosely the screw 30 thread 18 of the finish. Due to this loose engagement, it is not necessary that interior surface of the flange 12 conform to the variations in the container finish. The cap is applied to the finish and the wire edge 16 seats on the finishing ring 19 of the container, which is of the usual construction. It is to be particularly noted at this juncture, and is clearly shown in Fig. 2, that the top portion 11 and the liner 13 do not seat on the top of the finish, the depth of the 40 skirt being sufficient to hold the top portion and liner in spaced relation to the top of the finish.

A sleeve 20 having a plate 21 movable longitudinally thereof, is slipped over the cap and is brought to rest on the finishing ring 19. The 45 sleeve is concentric to the container and cap, and is contiguous to the outermost part of the thread 15 and the wire edge 16. The plate is seated on the top portion 11 of the cap 10.

With application of top pressure from any suitable source (not shown), the plate 21 moves downward and forces the top portion and liner to seat on the top of the finish 17, as shown in Fig. 3. Simultaneously, the flange 12 is collapsed between the screw threaded finish 17 and the 55

sleeve 20. The outturned bead 14 and the continuous thread 15 having been lightly drawn in the flange, as shown in Fig. 1, the flange will fold in process of collapse in a manner accentuating the bead 14 and the thread 15. As the sleeve 20 will prevent outward expansion of the folds, they are forced into the spiral recess between the ridges of the thread 15, and over the thread itself. Accordingly, after the application of top pressure on the cap, the flange will develop a thread conforming closely to the container finish, as shown in Figs. 3 and 4. The outturned bead 14, being the weakest part of the cap and having no support, readily collapses during the application of top pressure, allowing the liner to engage the bottle finish to form a tight seal.

In applying the cap flange to the outer surface of the finish in the manner described, all turning of the cap on the finish is avoided. Thus, the lacquer on the interior of the flange is not scratched nor marred. Further, the cap is brought down at uniform pressure on all parts of the top surface of the finish so that the liner effects a tight seal therewith and no creeping or wedging action can take place. The cap is caused to fit the individual finish to which it is applied, and any irregularities present in the finish are compensated for inasmuch as the flange of the cap follows the contour of the finish.

30 Modifications may be resorted to within the spirit and scope of my invention.

What I claim is:

1. The method of applying a cap having pre-formed threads outlined on the flange thereof to a threaded container finish, consisting in springing the cap loosely over the finish and applying top pressure thereto to collapse the cap onto the finish and thereby wholly form the cap threads to engage the finish threads, and confining the threaded portion of the cap by a surrounding sleeve having a smooth interior surface maintained in a fixed position concentric with said fin-

ish during the said collapse of the cap onto the finish.

2. The method of attaching to a container having an exteriorly screw threaded neck portion, a cap having a top portion and a depending skirt formed with shallow screw threads corresponding in number and arrangement to the threads on said neck portion, which method comprises placing the cap on the container and supporting it with the top portion thereof spaced above the top of the container, surrounding the threaded portion of the cap with a sleeve, and applying downward pressure to said top portion of the cap and thereby lowering it and simultaneously causing said top pressure to decrease the depth of said skirt and thereby deepen said shallow threads, causing each said deepened thread to conform to a corresponding thread on the container.

3. The method of attaching to a container having an exteriorly screw threaded neck portion, a cap having a top portion and a depending skirt formed with shallow screw threads corresponding to the threads on said neck portion, which method comprises placing the cap on the container and supporting it with the top portion thereof spaced above the top of the container, and applying downward pressure to said top portion of the cap and thereby lowering it and simultaneously causing said top pressure to decrease the depth of said skirt, and confining the threaded skirt against outward expansion during said lowering of the top portion of the cap, by a surrounding sleeve having a smooth interior surface maintained in fixed position concentric with said neck portion of the container during said collapse of the cap onto the finish, and thereby causing a deepening of said shallow threads and a conformation thereof to the threads on the container.
